(57) **CLAIM**

The ornamental design for a carrying strap, as shown and described.

DESCRIPTION

FIG. 1 is a perspective view of the carrying strap showing my new design in a representative operating environment.

FIG. 2 is a perspective view of the carrying strap showing my new design in a representative operating environment.

FIG. 3 is a front elevational view of my new design in a representative operating environment;

FIG. 4 is a top plan view thereof;

FIG. 5 is a left side elevational view thereof;

FIG. 6 is a right side elevational view thereof;

FIG. 7 is a back elevational view thereof;

FIG. 8 is a bottom plan view thereof; and,

FIG. 9 is a perspective view of a carrying strap showing an alternate embodiment of my new design in a representative operating environment.

The broken lines are directed to environment and are for illustrative purposes only. The broken lines form no part of the claimed design.
